Attorney.

UNITED STATES PATENT OFFICE.

BLAINE H. HARRIS, OF ST. PAUL, MINNESOTA, ASSIGNOR TO BROWN & BIGELOW, OF ST. PAUL, MINNESOTA, A CORPORATION OF MINNESOTA.

DESIGN FOR A TOY PAPER AEROPLANE.

57,647.

Specification for Design.

Patented Apr. 26, 1921.

Application filed June 3, 1920. Serial No. 386,362. Term of patent 7 years.

To all whom it may concern:

Be it known that I, BLAINE H. HARRIS, a citizen of the United States, residing at St. Paul, county of Ramsey, and State of Minnesota, have invented a new, original, and ornamental Design for Toy Paper Aeroplanes, of which the following is a specification, reference being had to the accompanying drawing, forming part thereof.

Figure 1 is a perspective view of the aero-plane, showing my new design.

Fig. 2 is a plan view of the same.

I claim:

The ornamental design for a toy paper aeroplane as shown.

BLAINE H. HARRIS.
